Att. 345

UNITED STATES PATENT OFFICE.

EDWIN E. SMEETH, OF OAK PARK, ILLINOIS, ASSIGNOR TO JENNIE H. SMEETH, OF OAK PARK, ILLINOIS.

AUTOMOBILE.

1,254,861.

Specification of Letters Patent. Patented Jan. 29, 1918.

Application filed January 8, 1917. Serial No. 141,328.

To all whom it may concern:

Be it known that I, EDWIN E. SMEETH, a citizen of the United States, and a resident of Oak Park, in the county of Cook, State 5 of Illinois, have invented certain new and useful Improvements in Automobiles, of which the following is a specification, reference being had to the accompanying drawings.

10 My invention relates to automobiles of the type driven by internal combustion engines, and it has for its principal object the provision of a new and improved arrangement of means for controlling the temperature of the cylinders, the carbureter, and other associated parts of the engine whereby a greatly improved volatilization of the fuel may be 15 procured with an attendant great efficiency in operation of the engine. In the operation 20 of an internal combustion engine in which cold air is taken directly through the radiator and thrown upon the cylinders, cold sections or zones are established in the radiator, permitting a portion at least of the 25 air to reach the cylinders, the carbureter, and the fuel tank with little if any pre-heating. This results in a decidedly inefficient 30 operation of the engine owing to the poor vaporization, poor mixing, &c., the number 35 of miles of travel attainable per gallon of fuel being correspondingly small. It is one of the objects of my invention to provide for leading the air to the radiator by a more or less circuitous route along which the air 40 will necessarily become warmed by mixture with previously warmed air and by contact with the radiator and other adjuncts of the engine. It is one of the more specific objects of my invention to provide an arrangement 45 by which the air is led a plurality of times through the radiator before it is directed upon the cylinders by the fan. It is another object of my invention to provide an arrangement providing removable baffle- 50 plates which can be employed during cold weather for protecting the cylinders from the cold air at the point of entrance of such air, serving to direct such cold air in a way to insure its being properly warmed before 55 coming in contact with the cylinders, such plates being adapted to be removed during warmer weather if their continued use proves to be unnecessary. It is another object of my invention to provide an arrangement providing an air space or oven in

front of the radiator, with means in connection therewith for feeding air thereto by an indirect route, means being provided for regulating the entrance of the cold air as may be desired without permitting it to pass directly upon the cylinders, the temperature of the engine being thus controlled. It is another object of my invention to provide sundry improvements as hereinafter pointed out. The preferred means by which I have 60 accomplished my several objects are illustrated in the drawings and are hereinafter more specifically described. That which I believe to be new and desire to cover by this application is set forth in the claims. 65

In the drawings:

Figure 1 is a plan view, partly in section, showing the arrangement of the engine of an automobile and illustrating the circulation of the air under the influence of the 75 fan;

Fig. 2 is a side elevation, partly in section, of the forward end portion of the part shown in Fig. 1; and

Fig. 3 is a view similar to Fig. 1, but 80 showing a modified form of construction.

Referring to Figs. 1 and 2, in which corresponding parts are indicated by the same reference characters,

10 indicates the dash-board of an automobile body, in front of which is suitably supported an internal combustion engine 11 of any suitable type inclosed within a hood 12 extending forward from the dash 10. The manifold 13 of the engine is connected with 85 a carbureter 14 to which gasoline or other fuel is fed by means of a pipe 15 leading from a tank 16 in position upon the dash 10. A radiator 17 of any suitable type is 90 located in front of the engine 11 for cooling the water circulating through the jacket of the engine 11, as is well understood in the art, the radiator 17 being provided with horizontal openings extending therethrough longitudinally of the automobile. A fan 18 100 is operatively connected with the engine 11 in any suitable manner so as to draw a quantity of air through the adjacent central portion of the radiator 17. The construction so far described is well understood in the 105 automobile art, and it is believed to be unnecessary to describe such parts in further detail herein.

In order to prevent the air, drawn through the central part of the radiator 17 by the fan 110

18, from passing directly backward through the radiator from the atmosphere without previous warming, I have provided a casing or oven 19, providing an air space 20 of some considerable size in front of the radiator. The casing or oven 19 is preferably removable so as to make it possible to lay such casing or oven aside when its use is unnecessary during warm weather. In connection with the casing or oven 19 I have also provided removable baffle-plates 21-22 at opposite sides of the engine extending backward from the radiator 17, such baffle-plates being adapted to control the air forced backward by the fan 18 so as to direct such air upon the cylinders of the engine, upon the carbureter 14, and upon the fuel tank 16. With the baffle-plates 21-22 in position, air is drawn from the air space 20 through the central part of the radiator 17. To take the place of the air so drawn backward through the central part of the radiator, other air is admitted to the hood through openings 23 in the side walls of the hood, being directed forward by the baffle-plates 21-22 so as to pass forward through the radiator 17 into the air space 20 in the casing or oven 19 where it is mixed with air which has been warmed by contact with the radiator.

30 By the provision of a circuitous path for the air through the hood and through the radiator before such air can be directed backward through the central part of the radiator and into contact with the engine, such air is warmed very considerably and is tempered so as not to have currents of cold air which would have a tendency to unduly cool parts of the engine. By reason of storing up within the hood an increasing quantity of heated air about the engine, the carbureter and the fuel tank, the vaporization of the fuel in the carbureter and about the spark plugs is very greatly improved, whereby a comparatively low test fuel can be employed with very good results. By this means I have been enabled to obtain substantially the same results during extremely cold weather as can be obtained during warm weather.

50 In order to control the temperature about the engine and the means for feeding gaseous mixture thereto, I have provided adjustable shutters at a plurality of points for admitting air as desired to the air space 20 and for releasing more or less of the hot air therefrom. In the construction shown in Fig. 2, an adjustable shutter 24 is provided across the upper end of the casing 19 through which the hot air is adapted to escape from the air space 20, a second adjustable shutter 25 being provided at the bottom of the casing or oven 19 for admitting cold air. In order to give the air admitted past the shutter 25 a longer and more circuitous path to that portion of the radiator

through which the air must pass backward under the influence of the fan 18, I have provided a baffle-plate 26 over the top of which the cold air from the shutter 25 must pass when such shutter is opened. By the provision of the shutters 24 and 25 and the baffle-plate 26 in connection with the baffle-plates 21-22, means is provided for controlling to a nicety the temperature of the air within the chamber 20 and within the hood 12 about the engine and its gas-feeding auxiliaries.

It will be understood that if occasion requires the shutter 24 may be opened in lieu of the shutter 25 for admission of air to the chamber 20.

By reason of the accumulation of heated air which can be brought about within the hood by the use of my improvements, and by reason of the means provided for regulating the temperature to the desired degree, it will be understood that the engine may, after being started and heated up with gasoline as a fuel, be continued in operation by the use of a lower grade fuel which will serve to give very high efficiency during a continued operation of the engine. If on the other hand the higher grade fuel be used continuously, the efficiency of the engine is maintained at a very high standard by reason of the great efficiency in vaporization of such fuel.

Referring now to Fig. 3, in which corresponding parts are indicated by the same reference characters, but with the addition of an exponent a , the construction is substantially the same as that shown in Fig. 1, except for the omission of the baffle-plates 21, 22 and 26. In place of the baffle-plates 21 and 22, removable baffle-plates 27 and 28 are employed, set at an angle, extending from the radiator 17 a to the side wall of the hood 12 a . In this position the baffle-plates 27 and 28 provide for a free admission of air through the forward ones of the openings 23 a and provide for the escape of the heated air through the openings 23 a at the rear end of the hood 12 a . By the omission of the baffle-plate 26 from the construction of Fig. 3, the path which the air must travel from the lowermost portion of the air space 20 a to the part of the radiator opposite the fan 18 a is shortened, but the principle of operation is still retained,—that is to say, the cold air is prevented from coming directly into contact with the central portion of the radiator under the influence of the fan 18 without having first come into contact with the heated surfaces and the heated air of the casing or oven 19 a , the extreme chilling of any section of the radiator being thus prevented.

So far as I am aware, I am the first in the art to provide a hot air space or oven directly in front of the central portion of the radia-

tor opposite which the ventilating fan is located, means being provided for admitting air from the atmosphere to such hot air space or oven through a more or less circuitous route, by which the air is prevented from flowing straight backward from the open atmosphere through the radiator, and by which the air which is forced backward by the fan through the radiator is first warmed by mixture with previously heated air and by contact with heated surfaces of the casing or oven, and my claims are to be construed accordingly.

What I claim as my invention and desire to secure by Letters Patent, is—

1. In an automobile, the combination of an internal combustion engine, a radiator in front of said engine, means for drawing air backward through said radiator and directing it upon said engine, and means for preventing air from passing backward through said radiator from the atmosphere without first passing partially across the front face of the radiator.
2. In an automobile, the combination of an internal combustion engine, a radiator in front of said engine, a casing providing an inclosed air space in front of said radiator, means for forcing air backward upon said engine from said air space, and means for admitting air to said air space at its edges only whereby such air must pass partially along the face of the radiator before it passes backward through the radiator.
3. In an automobile, the combination of an internal combustion engine, a radiator in front of said engine, a casing removably secured in position providing an inclosed air space in front of said radiator, means for forcing air backward through said radiator from said air space and directing it upon said engine, and means for feeding air to said air space at the edges thereof, comprising means for warming such air before it passes backward through the radiator into contact with the engine.
4. In an automobile, the combination of an internal combustion engine, a radiator in front of said engine, a casing providing an inclosed air space in front of said radiator, an adjustable shutter adapted to admit air to said air space at one edge thereof, means for causing the air thus admitted into the casing to have a circuitous passage therethrough, and means for forcing air backward through the radiator from said air space into contact with said engine.
5. In an automobile, the combination of an internal combustion engine, a radiator in

front of said engine, a casing providing an 60 inclosed air space in front of said radiator, adjustable openings adapted to admit air to said air space, means for causing the air admitted through one of said openings to have a circuitous passage through the casing, and means for forcing air backward 65 through the radiator from said air space into contact with said engine.

6. In an automobile, the combination of an internal combustion engine, a radiator in front of said engine, a casing providing an inclosed air space in front of said radiator, adjustable openings adapted to admit air to said air space at its uppermost and its lowermost edge portions, and means for forcing 70 air backward through the radiator from said air space into contact with said engine.

7. In an automobile, the combination of an internal combustion engine, a radiator in front of said engine, a casing providing 80 an inclosed air space in front of said radiator, an adjustable opening adapted to admit air to said air space at its lowermost edge, a baffle-plate adapted to direct the air admitted through said opening to the 85 upper portion of said air space before it can pass backward into contact with the radiator, and means for forcing air backward through the radiator from said air space into contact with said engine. 90

8. In an automobile, the combination of an internal combustion engine, a radiator in front of said engine, and means for directing and causing air to pass forward from the rear end portion of the engine 95 to said radiator and directly backward through the radiator into contact with the engine.

9. In an automobile, the combination of an internal combustion engine, a radiator 100 in front of said engine, substantially longitudinally-disposed plates arranged at opposite sides of said engine, and means for drawing air forward along the outer faces of said plates and directing it through the 105 radiator and into contact with the engine between said plates.

10. In an automobile, the combination of an internal combustion engine, a radiator in front of said engine, longitudinally-extending baffle-plates removably secured at opposite sides of said engine, and means for drawing air forward along the outer faces of said baffle-plates and for directing it through the radiator and into contact with 115 said engine between said baffle-plates.

EDWIN E. SMEETH.
